DENTIST DRILL CONTROL

Harry R. Clausen, Chicago, Ill.

Application October 21, 1940, Serial No. 362,031

5 Claims. (CL 32—23)

This invention relates to a surgical control device and more particularly to a device for controlling a dental drill unit.

It is an object of this invention to provide a surgical control device by which the surgeon or dentist in manipulating the surgical tool or appliance to perform the surgery may have positive finger-tip control of the tool or appliance.

Another object of the invention is to provide surgical tools, more particularly dentists' drills, with a control device which enables the surgeon or dentist to control by movement of his hands along or about the tool the operation of the tool itself.

More specifically, it is an object of this invention to provide a control device which enables the dentist, by a movement of the finger grasping his mirror or the hand piece of his drill, to control the operation of his drill.

Dental equipment now in use includes a foot switch which is used by the dentist to start and stop the motor of his drill. In working, a dentist must therefore maintain or support a large part of his weight upon one leg so that he may keep the other leg substantially free for instantaneous operation of the foot switch. This is both uncomfortable and at the same time, over a long period, detrimental to the health of a dentist.

It is therefore a further object of this invention to provide a dentist's drill with a control which permits the dentist to stand normally on his two feet and by means of his hands control the instantaneous starting and stopping of the drill without releasing the drill from his hand.

A further object of the invention is to provide a dental drill having a currentless control incorporated in the drill by which without danger of shock to himself or to the patient, the dentist may by movement of his hand or a finger and without releasing the tool, control the starting and stopping of the drill.

Other and further objects and advantages of the invention will be apparent from the following description when taken in connection with the accompanying drawing, wherein:

Figure 1 is a diagrammatic view in elevation of a dental unit embodying the present invention;

Figure 2 is a view in perspective of a dental mirror forming a part of the present invention;

Figure 3 is a view in perspective of a dental drill hand piece forming a part of the invention;

Figure 4 is a view in perspective of a contra angle attachment for a dental hand piece and illustrates the manner of adapting the contra angle to the present invention; and

Figure 5 is a schematic circuit diagram of a control device forming part of the present invention.

As shown in the drawing, the invention comprises a remotely controlled, control unit 2, an electrically operated or motor driven, surgical tool driving unit 4 controlled by the unit 2 and surgical hand tool remote controllers 6 and 8.

The control unit 2 preferably comprises a cabinet or housing 10 in which is mounted a thermionic vacuum tube 12 having a filament 14, a cathode 16, a control grid 18, a screen grid 20 and a plate or anode 22.

A cable 24 connects the control unit 2 to the electric operator or motor 26 of the surgical tool driving unit 4 and to the supply lines L—1 and L—2. In the modern dental unit the supply lines are housed within the stand 28 of the unit and therefore the cable 24 extends from the control unit 2 into the stand 28 where the connections are made to the motor 26 and the power supply lines. The conventional "foot switch" 30, which may be provided or retained as a presettable speed control and master switch, is connected to the motor and supply lines through a cable 32 extending into the stand 28.

Current is supplied to the filament 14 of the tube 12 from supply line L—1 through wire 34 of cable 24, wire 35 of the control unit, resistor or ballast tube 36, filament 14, wire 37, control switch 38, wire 40, and wire 42 of the cable 24 to the supply line L—2. One side of the filament 14 is connected to the cathode 16 by the wire 43 and to the control grid 18 through a resistor 44 and an air core choke coil or inductance 46.

A low voltage pilot lamp 48 is connected across a portion of the resistor 36 and serves to indicate the operative condition of the control unit. The pilot lamp 48 and the control switch 38 are mounted on the face of the cabinet 10 of the control unit which is positioned within easy reach and constant observation of the dentist as he is working.

The plate or anode 22 is connected to the power lead 35 through wire 52; resistor 54, wire 56, air core choke coil or inductance 58 and wire 60. The coils 46 and 58 are adjustably related so that the mutual inductance between the coils may be varied to cause the tube circuit to oscillate at a high frequency or to vary the value of the high frequency oscillating current within the circuit. The coils 46 and 58 constitute an adjustable feed back transformer coupling the plate circuit to the control grid circuit. Relays 55 61 and 62 have their coils 63 and 64 connected

in series across the resistor 54 by the wire 56 and a wire 66. A by-pass condenser 68 is also connected in shunt to the resistor 54 and a tuning condenser 70 is connected in shunt to the coil 58.

The switch of the relay 61 comprises a single pole double throw switch blade 72 and contacts 74 and 76. The contact 74 is connected to the supply line L-1 through the wire 78 of the control unit, the wire 80 of the cable 24, the wire 81 of the cable 32, the master switch blade 82 of the "foot switch" 30, the wire 83 of the cable 32, the wire 84, the motor commutator or rings and armature, the wire 85, the wire 86 of the cable 32, the wiper blade 87 of the adjustable resistor 88 in the "foot switch" 30, the wire 89 of the cable 32, the wire 90, the stator coils of the motor 26, and the wire 91 to the line L-1. The switch blade 72 is connected to the supply line L-2 through the wire 92 of the control unit and the wire 93 of the cable 24.

The relay 62 is a single pole, single throw, normally open time delay relay. The contact 94 of this relay is connected by the wire 95 to the contact 76 of the relay 61, the contact 76 being engaged by the blade 72 when the coil 63 is, in effect, deenergized. The switch blade 96 of the relay 62 is connected to the stator coils of the motor through resistor 98, wire 99, and wire 100 of cable 24 to wire 90 and is urged into engagement with the contact 94 when the coil 64 is, in effect, deenergized. A protective condenser 101 and resistor 102 are connected in series and across the switch blade 72 and contact 74 so that in breaking the circuit to the motor, no arc will be established between the blade 72 and the contact 74.

A surgical hand tool remote controller 6 comprises a dental mirror 103 having the usual cylindrical shank 104 of electrical insulating material such as Lucite which permits light to be directed through the shank onto the disc mirror. A small wire 105 extends through the center of the shank 104 and is connected at its inner end to a small electrically conducting, preferably copper, button, strip or contact piece 106 set into the surface of the shank and exposed so that the dentist may conveniently engage it with one of his fingers as he manipulates the mirror. At the upper free end of the mirror shank, the wire 105 is provided with a projecting contact pin or plug 107 adapted to receive a clip or contact cap 108 secured to one end of a fine wire 109 which may be provided with the usual insulating coating or covering. The wire 109 is plugged into the control unit 2 in which it is connected to one side of a blocking condenser 112. The other side of this condenser is connected by the wire 114 to the cathode end of the coil 46.

The surgical hand tool remote controller 8 comprises a dental drill hand piece 118, the steel sheath 120 of which is provided with a longitudinal groove having seated therein a fine insulated wire 122. The wire 122 at its lower end is connected to a small electrically conducting, preferably copper, button, strip or contact 124. The contact button 124 is mounted in a surface groove in the steel sheath 120 from which it is insulated as by the insulating coating or strip 126. The surface of the contact button 124 is exposed so that the dentist may conveniently engage the button with one of his fingers while holding the hand piece 118. The wire 122 at its upper end engages a conducting ring 128 mounted on, but insulated from, the steel sheath 120 just beneath the conventional operating and

mounting head 130 of the hand piece 118. It may be noted in respect to this operating and mounting head that it includes the mounting bracket 132 and a driven pulley 134 which through the spindle of the hand piece drives the drill or other surgical instrument 135. The ring 128 is connected to a fine, insulated wire 136 which is plugged into the control unit 2 in which it is connected to the condenser 112.

Figure 4 illustrates the manner in which the contra angle attachment 138 for the hand piece 118 may be equipped with an extension for the contact button 124 so that when the contra angle is employed, the control may readily be operated by the dentist with his fingers in the normal position in which he usually grasps the contra angle in use. Thus the contra angle 138 has attached thereto an insulated contact strip 140, a portion of the insulation of the strip being removed adjacent its lower end to expose a contact button 142. The insulation of the strip 140 is also removed from its lower surface adjacent its upper end so that when the contra angle is slipped over the lower end of the hand piece 118, this exposed part engages and makes electrical contact with the contact button 124.

The right angle hand piece attachment which is generally similar to the contra angle attachment 138, may in a similar manner be provided with an insulated strip such as 140 for the same purpose.

The inductive relation between the coils 46 and 58 may be varied by operation of the knob 144 secured to the adjusting shaft of these coils exteriorly of the cabinet or housing 10. The coils 46 and 58 may be mounted in any conventional manner providing a stationary support for one of the coils and an adjustable mounting bearing of course connected to the shaft which carries the operating knob 144. The control unit 2 may be mounted in any desirable convenient location, preferably adjacent to, on, or within, the stand 28. As shown in Figure 1, this control unit is mounted on the arm or bracket 146 which supports the tray and accessory table unit 148. The control unit may, however, be built directly into the stand 28 as will be apparent.

In operation the coils 46 and 58 are relatively adjusted so that the plate current through the relay coil 63 is sufficient to hold the relay switch blade 72 in its lowermost position engaging contact 76 and the motor 26 is deenergized.

When a surgeon or dentist presses his finger upon a contact button 106, 124 or 142, the current in the thermionic tube, high frequency oscillating or capacity controlled circuit decreases to such a value that the plate current to the relay coil 63 becomes insufficient to hold the blade 72 in contact with the contact 76 and the spring-impelled relay switch blade 72 moves into engagement with the contact 74. This completes a circuit to the motor 26 from the supply line L-1 through the wire 91, the stator coils of the motor 26, the wire 90, the wire 89, the resistor 88 and wiper 87 of the "foot switch" 30, the wire 86, the wire 85, the armature of the motor 26, the wire 84, the wire 83, the master switch 82 of "foot switch" 30, the wire 81, the wire 80, the wire 78, the contact 74 and blade 72 of relay 61, the wire 92 and wire 93 to supply line L-2. The motor 26 therefore is now energized and drives the drill or other surgical instrument 135. As soon as the dentist raises his finger from engagement with the contact button 106, 124, or 142,

the current in the thermionic tube oscillating circuit increases instantaneously and the blade 72 snaps to its normal position, engaging contact 76. The circuit to the motor 26 is broken as soon as the switch blade 72 leaves the contact 74. When the blade 72 engages the contact 76, the circuit is completed to the stator coils of the motor through the resistor 88 while the armature is deenergized thereby to dynamically brake the motor so that the motor very quickly comes to rest. This circuit is completed from the line L-1 through the wire 81, the stator coils, the wires 90, 100 and 89, the resistor 88, switch blade 86, the contact 84, the wire 85, the switch contact 76, the blade 72 and wires 82 and 93 to the supply line L-2. When the current becomes sufficient to operate relay 61, it also operates relay 62 to move its switch blade 96 out of engagement with its contact 94, but the relay 62 being a delay relay, holds its contact closed until the motor is brought to rest and then automatically opens to open the dynamic braking circuit.

In some cases it may be desirable that the surgical hand tool be operated only when brought into close relation to the patient or when the patient is touched by the surgeon or dentist. Thus for example, it is frequently necessary that the operation of the drill be not initiated until it is brought into the cavity or into juxtaposition to the tooth to be drilled. It is also desirable for the further positive protection of the patient against inadvertent cutting by the instrument or drill, that it be automatically stopped while being withdrawn or when the surgeon or dentist moves away from the patient.

In such cases, the coils 46 and 58 may be adjusted relatively so that the oscillating current, when the button 106, 124, or 142 is engaged, is not reduced sufficiently to release the relay 61, but when the dentist places one of his hands near or in contact with the patient as when he places the mirror or drill in the patient's mouth, the current of the oscillating circuit becomes sufficiently reduced to release the relay 61 and energize the motor 26. If the drill bit should become stuck in the patient's tooth so that it could not be withdrawn quickly, the drill motor may still be deenergized by the dentist by simply removing his finger from the contact button 106, 124, or 142.

In some cases as when using the mirror in drilling operations, it becomes desirable to have the control exercised through the hand holding the mirror, rather than through the hand holding the drill hand piece. In such case, only the wire 109 of mirror controlling unit 6 need be plugged into the control unit 2 to determine the operation of the oscillating circuit and determine the operation of the motor 26.

The coils 46 and 58 may be so adjusted relatively that an increase or decrease in the pressure with which the contact button is engaged will cause a starting or stopping of the motor, and therefore the control may be effected without actually disengaging the contact button.

By physical engagement of the contact button by the surgeon or dentist, or by increase in the pressure of the engagement, the capacity to ground from the coil 46 is varied to cause the circuit to stop oscillating or oscillate feebly. Any suitable part of the oscillating circuit may be directly connected to ground. For example, the cathode 16 may be directly grounded by the wire 152 (Figure 5), or suitable ground connection 75

may be established through that one of the supply lines which is always grounded.

For the purpose of illustrating the invention, the same has been shown as embodied in a dentist's equipment for the control of the operating motor of the dentist's hand drill. However, it will be apparent that the invention may be embodied in other surgical equipment, including other surgical hand tools, so that the operation of tools may be maintained under the control of the hand which holds the tool. Thus, for example, the remote controlling unit may comprise a chiropodist's cutter tool in which there is provided a small copper electrically conducting button, strip or contact piece similar to the contact button 124 and similarly mounted on the hand piece of the cutter so that through the control unit 2, the electric cutter drive mechanism or motor may be controlled.

It should be pointed out that no current flows from the control unit through the small wire to the contact button of the hand tool, nor does any measurable voltage, capable of providing an electric shock, exist between the contact button and ground, and hence the tools may be handled with absolute safety and in the same manner as formerly.

For illustrative purposes, it may be stated that in a particular case, the oscillating circuit embodied a thermionic tube known as "25 L6GT," and the impedances of the circuit had the following values:

Coil 46, 16 millihenries;
 Coil 58, 8 millihenries;
 Condenser 68, 10 microfarads;
 Condenser 70, .0002 microfarad;
 Condenser 101, 1 microfarad;
 Condenser 112, .003 microfarad;
 Resistor 36 was a ballast tube providing a 92 volt drop at the rated filament current of the tube 12;
 Resistor 44 was of $\frac{1}{4}$ megohm;
 Resistor 54 was of 1,000 ohms;
 Resistor 102 was of 500 ohms;
 The voltage of the supply lines was on the order of 110 to 120 volts.

Obviously, the invention is not limited to the specific disclosure herein but is capable of other modifications and changes without departing from the spirit and scope of the appended claims.

The invention is hereby claimed as follows:

1. A surgical device comprising a driven surgical instrument, an electric motor for driving said instrument, a relay controlling the energization of said motor, a high frequency oscillation generating circuit controlling said relay, a surgical hand tool having an exposed electrically conducting member connected to said oscillation generating circuit and positioned for engagement by the operator's hand while holding the tool to control said oscillation generating circuit whereby to control said relay, and a circuit completed by said relay upon deenergizing of said motor for dynamically braking said motor.

2. A surgical appliance comprising a member having a shank adapted to be grasped in the hand, an electric conducting member embedded in the shank of the tool and electrically exposed for engagement by the hand while grasping the appliance and electric conductor means insulated in the shank of the appliance but extending outwardly therefrom for connection to a capacity responsive control unit of an electrically driven surgical instrument.

3. An electrically driven surgical cutter comprising a cutter receiving member having a shank adapted to be grasped in the hand, an electrically conducting member having a portion embedded in the shank and electrically exposed for engagement by a finger of the hand grasping the shank, and means for connecting said electrically conducting member to a capacity responsive control unit adapted to control the electrically driven surgical cutter.

4. A dental device comprising a drill receiving hand tool, a motor for driving the drill, a foot control including presettable means connected to said motor for controlling the speed of said motor, a relay connected to said motor and said foot control for energizing and deenergizing said motor and said foot control, a capacity responsive high frequency oscillation generating circuit connected to said relay, said hand tool having a shank, variable capacity control means for said oscillating circuit, said variable capacity control means comprising electrically conducting means connected to said oscillation generating circuit and including an electrically exposed member carried by the shank of said hand tool for engagement by the hand while holding the tool, and

5 a time delay relay controlled by said oscillation generating circuit and connected to said first relay and said motor for establishing a dynamic braking circuit through the motor upon deenergization of said motor by the first relay and automatically opening said dynamic braking circuit upon the lapse of a predetermined time.

10 5. A dental device comprising a dental drill, said drill having a shank adapted to be grasped in the hand, an electrically conducting member embedded in the shank and having a portion exposed for engagement by the hand while grasping the shank, and a contra-angle attachment for said drill, said attachment having an insulated, electrically conducting member fixed thereto and adapted to extend therefrom longitudinally of the drill shank, a portion of said member being exposed for engagement with the electrically exposed portion of the electrically 15 conducting member embedded in the shank of the drill and having a second exposed part for engagement by the hand while grasping the drill with the contra-angle attachment secured thereto.
